AUXILIARY CARBURATION FOR INTERNAL COMBUSTION ENGINES

Arlington Moore, New York, N. Y., assignor, by
mesne assignments, to Maxmoor Corporation,
New York, N. Y., a corporation of Delaware

Application May 4, 1932, Serial No. 609,114

19 Claims. (CL 123—119)

My invention relates to methods of and means for supplementing the carburator in supplying fuel to internal combustion engines at certain stages of engine operation, and the same 5 has for its object to make provision for insuring quick engine starting, and preventing engine stumbling or stalling during the operation thereof.

Another object of the invention is to effect the 10 introduction of adequate fuel for cold engine starting without reliance on pressure reduction in the intake, obviating the use of a choke, and thereby supplying the requisite fuel for starting without unduly restricting the air supply.

Another object of the invention is to effect the 15 positive introduction of supplementing fuel into the engine intake without reliance on the pressure reduction therein at stages of engine operation when the engine suction is insufficient to deliver the requisite fuel from the carburator 20 for maintaining engine operation.

Another object of the invention is to effect 25 such positive introduction of supplementing fuel in response to pressure conditions within the intake.

Another object of the invention is to differentially control the admission of supplementing fuel to satisfy the fuel requirements either for 30 cold engine starting or for operation when the engine is warm.

Other objects will in part be obvious and in part be pointed out hereinafter.

In the accompanying drawings:

Figure 1 is a front elevation of a carburing 35 and mixture distributing system having applied to the intake manifold thereof one form of device constructed according to and embodying my invention;

Fig. 2 is a side elevation thereof, with parts in 40 section;

Fig. 3 is a diagrammatic view showing my device applied directly to the casting of an anterior throttle carburator;

Fig. 4 is a diagrammatic view showing my device applied to the casting of the ordinary carburator of the posterior throttle type;

Fig. 5 is an elevation of the device;

Fig. 6 is a plan thereof with parts in section;

Fig. 7 is a section thereof on the line 7—7 of 50 Fig. 5, showing the fuel admitting valve in partly open position;

Fig. 8 is a diagrammatic view of the device showing the valve in fully open position; and

Fig. 9 is a like view showing the valve in closed 55 position.

Referring to the drawings, I have shown my auxiliary fuel device 10 applied to or associated with a carburator and charge mixture distributing system, such as disclosed in my copending application, Serial No. 525,992, filed March 28, 1931, although the device may be used with all types of carburators.

In the particular system illustrated as one example of the application of the device, the carburator 12 is of the downdraft anterior throttle type in which the fuel nozzle 14 is located at the engine side of the throttle 16, the fuel flow being controlled as described in said application Ser. No. 525,992.

The carburator 12 is secured to the intake 15 manifold 18 for distribution of the charge mixture to the several cylinders, and said manifold at the juncture of the branches thereof is preferably so associated with the exhaust manifold 20 as to form heating means 22 subject to exhaust gas heating so as to vaporize any fuel particles that may be thrown out of the charge mixture upon deflection thereof into the branches. The details of construction and mode of operation of said heating means 22 are described in said application Serial No. 525,992.

Fuel is supplied in the usual manner to the carburator 12 from the low level fuel tank 24 to the float chamber 26 of the carburator by means of the pump 28 located in the fuel line 30 which communicates at 32 with the float chamber 26.

The fuel pump 28 may be of any type, operated electrically or mechanically, and begins to function immediately upon the turning over of the 35 engine by the engine starter, the pumping means 28 shown being of the diaphragm type which is actuated in the usual manner from the crankshaft of the engine.

In my invention I effect the introduction of 40 supplementing or augmenting fuel at certain stages of engine operation without reliance on intake pressure reduction or suction, and utilize for this purpose the same fuel impelling force which effects the delivery of fuel to the carburetor float chamber.

I am thus able to start the engine cold without utilizing pressure reduction for inducing fuel flow, as by an air choke, and when the engine suction is so low at certain stages of engine operation that the fuel from the carburator tends to lean out to cause engine stumbling or stalling, the fuel required to maintain engine operation is impelled into the intake without reliance on suction or pressure reduction in the intake. The 55

fuel pump 28 is thus utilized to supply the fuel to the carburetor during normal operation for fuel introduction into the intake conduit in response to suction variations on the fuel jet, and when the suction cannot be relied on, such pumping means effects the introduction of fuel into the intake directly without reliance on suction or pressure reduction.

The bypassing of the auxiliary fuel into the intake is preferably controlled by valvular means which may be actuated either manually, or automatically, or both.

The stages of engine operation at which the main carbureting means should be supplemented to supply additional fuel are at engine starting, during the warming up period, upon acceleration, at low speed full load operation, as under heavy lugging conditions, and, in general, at stages of engine operation when the normal suction on the fuel jet is inadequate to induce sufficient fuel flow, particularly when the intake pressure substantially approaches or is substantially at atmospheric pressure.

In my method I control the introduction of the impelled auxiliary fuel during normal engine operation in response to and by intake depression so that at small intake depression the additional fuel required is supplied to maintain a mixture ratio productive of efficient engine operation at such stage of engine operation without reliance on any manual manipulation.

In starting the engine cold, provision is made for manually enlarging the auxiliary fuel passage, available also at any state of operation, supplementary to the automatic control thereof so that the obtaining of the rich mixture required for engine starting or priming is insured. Upon starting, the fuel is positively pumped or forced through the auxiliary passage directly into the intake conduit immediately upon turning over the engine by the starter or upon closing the circuit of the pumping means as by the ignition switch, if the pumping means is operated electrically.

By my method of supplementary fuel introduction I am able to supply adequate air to the engine upon engine starting, the control of the air by the throttle being entirely independent of the fuel introduction. The positive introduction of fuel upon starting without reliance on pressure reduction in the intake, dispenses with the usual air choking means, or similar expedients, for the purpose of inducing fuel flow for starting by pressure reduction, and the air passage can thus be adjusted to allow the engine to breathe adequate air. Adequate fuel for engine starting can thus be obtained without unduly restricting the admission of the air component.

By auxiliary fuel introduction upon engine starting without reliance on pressure reduction in the intake obtained by air choking or throttling, I am able to introduce more air into the cylinders producing higher compression pressures and more heat, enabling the engine to warm up quickly.

The auxiliary fuel may be delivered into the intake conduit at any suitable point at either side of the air or mixture throttle, but is preferably delivered directly into the intake manifold itself close up to the juncture of the branches, as shown at Figs. 1 and 2. The fuel as thus delivered is available instantly for discharge into the intake ports of the engine, and such fuel, when the device 10 is installed on a manifold,

such as shown, discharges in proximity to the heating means 22 to facilitate fuel vaporization.

If so desired, the pressure responsive fuel passage controlling device 10 may be associated with the carburetor casting itself at the engine side of the throttle 16^a, as shown at Fig. 3, illustrating a carburetor 12^a of the anterior throttle type, or such device may be connected to the casting of the carburetor 12^b for introduction of fuel into the intake conduit at the atmospheric side of the throttle 16^b, as shown at Fig. 4, the carburetor 12^b being of the posterior throttle type.

The pressure responsive device 10 for controlling the passage of fuel from the main fuel tank 24 into the intake comprises a casing formed from members 34 and 36 secured together by screws 38 and providing a chamber 40 therebetween. A diaphragm or other pressure responsive means 42 of suitable material, such as light brass, leather or other composition is clamped between the members 34 and 36, or otherwise received therebetween, the diaphragm bisecting the chamber 40. A cylindrical valve member 44 having a tapered end 45 is secured centrally to the diaphragm 42 and is adapted to work in a bore 46 in the member 36 which bore terminates in an apertured valve seat 48, adapted to be closed by the end 45, for delivery of fuel into the intake conduit. Fuel is delivered through passage 50 into the outer end of bore 46 for discharge through orifice 48. The passage 50 opens into the bore 46 through orifice 52 at a point inwardly of the valve seat 48. The fuel passing through seat 48 is preferably discharged through a suitable nozzle 53 having small openings therein for discharging the fuel as a spray into the air at a point spaced from the walls of the conduit. Fuel is supplied to passage 50 from the line 30 through a bypass portion 54, Fig. 1, adapted to be secured into the threaded end portion 56 of passage 50.

The inherent resiliency of the diaphragm 42, augmented by a separate spring if so desired, tends to hold the valve member 44 in the open position shown at Fig. 7. The diaphragm 42 divides the chamber 40 into two parts 58 and 60. The part 58 communicates with the intake through a passage 62 disposed with the bore 46 in the threaded boss 64 adapted to be screwed into a suitable opening in the intake conduit to which the device 10 is to be secured. In case the device is connected to the carburetor casting at the atmospheric side of the throttle as shown at Fig. 4, I provide a pressure conduit, such as 62^a from the chamber 58 to the intake at the engine side of the throttle. The chamber part 58 is thus subject to the pressure reduction in the intake, chamber part 60 being vented to atmosphere.

When the pressure reduction in the intake exceeds a given amount, say 1" H₂O, the carburetor then being able to operate efficiently, the valve member 44 closes as shown at Fig. 9 to seal both orifices 48 and 52, providing a double seal to prevent passage of fuel through the bypass 54 and into the intake by action of the pump 28.

When the valve 44 closes the inwardly directed abutment portion or shoulder backing 66 serves to support the diaphragm 42 to prevent undue distortion thereof when the pressure reduction is great, thereby relieving the diaphragm of strain, and insuring return of the diaphragm to normal position as the pressure reduction lessens. The backing 66 receiving the thrust of the diaphragm also takes such thrust off of the valve seat 48 thereby preventing peening action by the valve 44 against the valve seat liable to injure the

valve and seat interfering with proper closing thereof.

The opening of the valve 44 at small depression in the intake is adjusted or regulated to control the fuel supply by suitable means 68. This means comprises a bowed leaf spring 70 secured at one end by a screw 72 and retained in place by and within the reduced channel portion 74 of the member 34, the opposite end of the spring 70 slidably engaging the inner end of an adjusting screw 76. The spring 70 bears against the end of a stem 78 secured to the diaphragm 42, said stem 78 serving as means for securing the valve 44 to the diaphragm through a threaded connection, as shown at 80. When the valve 44 opens, the amount of fuel passing into the intake depends on the extent of opening of the orifice 52 as determined by the adjusted position of the spring 70 serving as an abutment for the stem 78, the orifice 52 being the fuel controlling or metering orifice. The fuel supplied through the auxiliary device may thus be regulated to satisfy the requirements for additional fuel at periods of least depression in the intake during warm engine operation.

I also provide means 82 for manually actuating the pressure responsive device 10 to open the valve 44 at will. This means comprises a cam or tapered key slide 84 riding through and guided by slots 86 in the member 36 and also extending through a slot 88 in the stem 78. The member 84 is provided with stops 90 at the opposite ends thereof to retain the same against withdrawal from the casing of the device 10 and to limit the movement thereof in both directions, and is actuated from a distant point, such as from the instrument board by means of a wire 92 guided through a tube 94 and attached to member 84 at 95.

In the position of the key 84 shown at Figs. 6, 7 and 9, the reduced portion 96 thereof is received by the stem 78 and the device 10 is free for automatic operation. When the wire 92 is pulled for engine starting the enlarged portion 98 enters the slot 88 and retracts the valve 44 to the desired maximum extent as shown at Fig. 8, to allow the supplying of the maximum amount of fuel by the pump 28. When the valve 44 is thus retracted the spring 70 yields sufficiently to allow such retraction. When the engine has warmed after starting the wire 92 is pushed back to allow automatic operation of the pressure responsive device.

The fuel metering orifice 52 is of such size as to allow when fully open the passage of the maximum amount of fuel to supply the rich fuel required for starting the engine cold. After the engine is started and warms up, the valve 44, adjusted at 68, controls the extent of opening 60 of the orifice 52 to allow the passage of such lesser amount of fuel as is required to supplement the carburetor when the intake depression is least.

The spring 70, which determines the normal or partially open position of the valve 44, yields when the member 84 is actuated, and when the latter releases valve 44, such spring serves in the absence of depression to return the valve to its normal partially open position as determined by the adjustment 76.

In operation, when the intake depression exceeds a given value, say 1" H₂O, the valve 44 is closed under the action thereof and the main carburetor is supplying all the fuel required. Should at any stage of engine operation the in-

take depression become less than that capable of inducing adequate fuel from the carburetor, the valve 44 opens to the extent predetermined by the adjustment, as shown at Fig. 7, to allow the pumping in of the auxiliary fuel required to maintain the engine in operation.

My device is particularly adapted for supplying additional fuel when the throttle is suddenly opened wide, causing a corresponding drop of intake depression to substantially atmospheric pressure. This prevents engine stumbling or stalling during acceleration, additional fuel being pumped in until the engine acquires such speed as to insure efficient carburetor operation. As the intake depression increases the valve 44 starts to close to gradually reduce the supply of auxiliary fuel. Fuel is thus supplied to the engine without reliance on induction when the suction on the carburetor jet is insufficient to supply the required fuel.

The device embodying my said invention also prevents engine stalling under heavy lugging conditions of engine operation, as when the engine is operating up a steep grade, the throttle being wide open and the engine developing its maximum torque. As the speed of the engine decreases and the intake depression approaches the minimum close to atmosphere, the valve 44 automatically opens in response to the pressure conditions to supply the fuel which the carburetor now is incapable of delivering. As the engine overcomes the grade, it immediately speeds up, and as the intake depression increases the auxiliary fuel supply gradually diminishes in inverse relation to depression until it reaches zero and the carburetor functions normally. The device can also be relied on to operate automatically to keep the engine from stalling during the warming up period without reliance on the manual control, or should the engine stop and be restarted while warm.

The device of the present invention is simple in construction and may be readily installed for use on various types of engines and carburetors. The device is reliable in operation, lessens danger of accidents in the use of automobiles, enables quick starting and quick pick-up in traffic, and insures against engine stumbling or stalling under conditions when the main carburetor is liable not to supply the requisite fuel for maintaining the engine in operation.

I am thus able to start the engine without the use of a choke, obviating the necessity for unduly restricting the air supply, and obviating the danger of lubricating oil dilution, and I can maintain the engine in operation when the suction is insufficient to draw adequate fuel from the carburetor, the operation being automatic so that such auxiliary fuel is always delivered at times when the carburetor fails to supply the requisite fuel.

Having thus described my invention what I claim and desire to secure by Letters Patent is:

1. The hereindescribed method of carburation for internal combustion engines which comprises impelling main fuel to a higher level for introduction into the intake conduit by engine suction, and at certain stages of engine operation effecting the introduction of auxiliary fuel into the intake conduit in response to pressure conditions therein by the action of the main fuel impelling force.

2. The hereindescribed method of carburation for internal combustion engines which comprises impelling main fuel to a higher level for intro-

- duction into the intake conduit by engine suction, and when the suction is low introducing in response to such suction condition auxiliary fuel into the intake conduit by the action of the main fuel impelling force without reliance on engine suction for inducing fuel flow.
3. The herein-described method of supplying fuel to the intake conduit of internal combustion engines which comprises effecting the introduction of main fuel into the engine by the pressure differential on a constant level source of supply while replenishing the constant level source of supply by pumping fuel from a lower level, and under operating conditions productive of very low intake depression and in response to such lowered intake depression by-passing a portion of the fuel and delivering the same directly into the intake conduit by said pumping action.
4. The herein-described method of carburation for internal combustion engines which comprises impelling fuel from a lower level to a higher level for introduction of main fuel into the intake conduit by engine suction, and effecting at periods of low engine suction the direct introduction of auxiliary fuel into the intake conduit by said impelling action in response to and by pressure conditions in the intake conduit.
5. The herein-described method of carburation for internal combustion engines which comprises impelling fuel by engine operation from a main source of supply to a higher elevation for delivery of main fuel into the intake conduit by engine suction, and at periods of low engine suction controlling the passage of fuel in response to and by the pressure reduction in the intake conduit and effecting thereby the delivery of auxiliary fuel into the intake conduit by said impelling action.
6. The combination with an internal combustion engine including intake conduit, carburator and pumping means for supplying the carburator with fuel from a main source of supply, of means for supplying auxiliary fuel by the action of said pumping means to the intake conduit from said main source of supply, valvular means normally biased to open and responsive to changes in conditions of engine operation for automatically controlling the passage of auxiliary fuel, and means for manually actuating said valvular means.
7. A device of the character described comprising means for delivering auxiliary fuel to the intake conduit of an internal combustion engine, a valve controlling the passage of auxiliary fuel, pressure responsive means for controlling said valve to cause opening thereof under conditions of low intake suction and closing thereof at higher suction, and means for manually actuating said valve.
8. A device of the character described comprising means for delivering fuel to the intake conduit of an internal combustion engine, a suction operated valve for controlling the passage of fuel, said valve being biased to open when the suction is low, and manual means for actuating said valve to enlarge the opening thereof.
9. A device of the character described comprising means for impelling auxiliary fuel into the intake conduit of an internal combustion engine, a suction operated valve for controlling the passage of auxiliary fuel, said valve being biased to move to a given open position when the suction is low, and manual valve actuating means operable
- from a remote point for enlarging the extent of valve opening at engine starting.
10. The combination with an internal combustion engine including intake conduit, carburator and means for impelling fuel from a low level source of supply to said carburator, of means between said fuel impelling means and the intake conduit for delivering auxiliary fuel to the intake, and a suction operated valve for controlling the passage of fuel through said auxiliary fuel delivering means, said valve being open when the suction is low.
11. A device of the character described comprising means for supplying auxiliary fuel to the intake conduit of an internal combustion engine, a valve for controlling said means, pressure responsive means for closing said valve, said valve being spring biased to open when the engine suction is low, and means for adjustably limiting the extent of opening of said valve.
12. A device of the character described comprising a casing, a fuel passage in the wall thereof, a diaphragm in said casing actuated in response to intake depression, a valve on said diaphragm and controlling said passage to open the same at low intake depression, and means on the casing to prevent distortion of the diaphragm under high intake depression.
13. A device of the character described comprising a casing having a fuel passage in the wall thereof, pressure responsive means in the casing operated in response to intake depression, valve means operated by said pressure responsive means for controlling said passage and opening the same when the intake depression is low, spring means engaging the valve means for adjusting the open position thereof, and a slide cam for increasing the opening of said valve means against the resistance of said spring means.
14. The herein-described method of carburation for internal combustion engines which comprises forcing maximum auxiliary fuel into intake air by the action of the impelling force supplying fuel to the carburator and operated upon the turning over of the engine, and as the engine attains normal operating conditions restricting the passage of auxiliary fuel in response to increases in suction.
15. The herein-described method of carburation for internal combustion engines which comprises directly forcing auxiliary fuel into the intake air when the engine suction is low by the action of the impelling force supplying fuel to the carburator, and thereby curing deficiencies in the flow of main fuel, controlling the passage of auxiliary fuel in response to pressure conditions in the intake to prevent auxiliary fuel introduction when the suction is ample for inducing main fuel flow, and during the warming up period at engine starting effecting the introduction of maximum auxiliary fuel.
16. The combination with an internal combustion engine including intake conduit, carburator, and means operated with the engine for impelling fuel from a low level supply to said carburator, of means including a passage for bypassing fuel under the action of said fuel impelling means around the carburator into said intake conduit, and valvular means responsive to changes in intake depression during engine operation for controlling said passage to open same when intake depression is below a predetermined

value and to keep it closed when such value is exceeded.

17. The combination with an internal combustion engine including intake conduit, carburetor and means for impelling fuel from a low level to said carburetor, of means for bypassing auxiliary fuel by said impelling means directly into said intake conduit, valvular means for controlling the passage of said auxiliary fuel responsive to changes in suction conditions to open at low suctions and to close at higher suctions, and manual means for enlarging the valve opening upon engine starting.

18. A device of the character described comprising means for impelling auxiliary fuel into the intake, means responsive to suction conditions and biased to open at low suction, closing at higher suctions, a spring abutment for limiting the opening movement of said pressure responsive means, and manual means for actuating

said pressure responsive means to effect opening movement thereof, said manual means coacting with said pressure responsive means to allow in a certain position of the manual control automatic operation of the pressure responsive means.

19. The combination with an internal combustion engine including an intake conduit having a hot spot at the juncture of the branches thereof, a carburetor, and means operated by the engine for impelling fuel from a low level to said carburetor, of means for bypassing auxiliary fuel by said impelling means directly into the intake conduit contiguous to said hot spot, and means responsive to changes in suction for controlling said bypassing means to open the same at low suctions and to close the same at higher suctions.

ARLINGTON MOORE.

20
